UNITED STATES PATENT OFFICE

WILLIAM TOMAS PEEK AND LOVELACE PRESTON EUBANKS, OF ATLANTA, GEORGIA

WASHING AND SANDING MACHINE

Application filed May 4, 1931. Serial No. 535,040.

This invention relates to a cleaning and scouring implement; and more particularly, to a device for use in connection with the cleaning of automobiles and the like, in which it is desirable to scour lightly as with a brush while water and a proper detergent is applied. The device can readily be used where greater friction is necessary and in connection with abrasives, such as sand paper, without substantial modification, where, for instance, it is desired to entirely remove the paint or finish.

The object of the invention is to provide a power driven, hand manipulated tool of the character indicated of an improved and simplified structure adapted to operate with great efficiency and to be handled and applied with ease.

The invention consists in the novel construction, arrangement and combinations of parts as hereinafter more specifically described and claimed.

Two sheets of drawings accompany this specification as part thereof, in which like reference characters indicate like parts throughout.

In the drawings:

Figure 1 is a longitudinal cross section through the improved implement taken on line 1—1 of Figure 2;

Figure 2 is a transverse vertical cross section on line 2—2 of Figure 1;

Figure 3 is a fragmentary vertical longitudinal cross section through the air supply conduit;

Figure 4 is a transverse cross section through the nozzle on line 4—4 of Figure 1;

Figure 5 is a vertical transverse cross section taken on line 5—5 of Figure 1; and

Figure 6 is a side elevation of a modified tool for use with the device.

Referring to the drawings, the improved cleaning device comprises a housing formed in two main parts 1 and 2, each of which is provided with a peripheral flange 3, which

flanges are secured in abutment by bolts 4. Each of the parts of the housing 1 and 2 are provided with centrally positioned aligned bearings 5 for a shaft 7. Part 2 of the housing is provided with a cylindrical chamber 8 in which slides a piston 9 having a suitable packing ring 10. The piston 9 slides upon a centrally positioned rod 11, and the rear and open end of the chamber 8 is adapted to be closed by a handle 14 having an enlarged disc part 14' threaded to mate with the threads 15 to secure the handle 14 with relation to the member 2. Handle 14 is provided with a central chamber 16 into which guide rod 11 extends and a spring 18 is positioned in this chamber so as to bear against the piston 9. The rod 11 is positioned centrally of chamber 8 by a seat 17 in handle 14.

A conduit 19 is provided through housing members 1 and 2 and through an extension nozzle 8' provided on housing 1, this conduit 19 connecting at the rear with a pipe 20, controlled as by valve 21, and is adapted to receive water from any suitable source through flexible tubing connected with pipe 20.

A turbine wheel 22 is fixedly secured to shaft 7 being provided with blades 23 and compressed air is conveyed to this turbine wheel for driving the same through a conduit 24, which is connected at the rear of housing 2 with a supply pipe 25 associated with a control valve 25'.

Conduit 24 progressively expands in diameter and at its forward end adjacent turbine wheel 22 is arranged to communicate simultaneously with two of the blades 23, as is well illustrated in Figure 2. On the exhaust side of these two blades is a reversal conduit 26 shown attached as by screws 26', which has a progressively expanding bore receiving the exhaust air from the two blades, and communicating at its posterior end with four of the turbine blades 28, delivering the residual energy of the exhaust

to these four blades simultaneously, thus leading the compressed air through the turbine twice in two stages of expansion.

The compressed air pipe 25 is provided at the end of housing 2 with a by-pass pipe 30 controlled as by valve 31, which pipe discharges between the disc of handle 14 and piston 9, thus impelling piston 9 forwardly within chamber 8, which chamber is adapted to receive a liquid detergent, such as soap. The chamber 8 communicates by passage 33 with nozzle 8' and discharges at the end of said nozzle adjacent the discharge of conduit 19, conveying water.

15 The chamber 8 can be refilled with soap, as though hole 35, normally closed by bolt 36. On the forward end of shaft 7 is secured a sleeve 38 as by screw 39 which sleeve 38 is provided at its forward end with a bayonet slot 41. A brush 42 having bristles 43 and a stud 44 provided with a pin 45 is adapted to be secured in interlocked position with sleeve 38 to be rotated by shaft 7 and the nozzle 8' is of a length and so positioned as to discharge water or water and soap upon the expanded bristles of the brush when the same is pressed against a surface for cleaning purposes.

30 Where it is desired to apply greater friction than can be secured with a brush, a disc 47 is provided having a similar stud 44 with pin 45, but adapted to be covered with a sheet of sand paper, emery cloth or the like, which is secured as by a band 48 having its ends provided with lugs 51 adapted to be secured as by thumb bolt 52. A bayonet slot 50 in the band 48 and pin 49 on disc 47 securely lock band 48 with respect to disc 47.

40 In operation, the opening of valve 21 will permit the discharge of water through nozzle 8' without the rotation of brush 42. If it is desired to rotate brush 42 with only the water being supplied, the valve 31 will be closed and valve 25' opened to supply compressed air to turbine wheel 22 and rotating brush 42. If it be desired to supply a detergent with the water, valve 31 will be opened thereby supplying compressed air behind the piston 9 and thus forcing soap through conduit 33 to be discharged adjacent the water from the end of nozzle 8'.

45 The implement can be conveniently handled at all times by handle 14.

50 Various modifications in the precise construction and arrangement of parts will readily suggest themselves to those skilled in the art, but within the scope of the present invention as claimed.

55 What we claim is:

1. In a portable cleaning device, a housing, a brush carried by the housing, a cylinder and piston in the housing, a conduit leading from one end of the cylinder and discharging adjacent the brush, and means

for applying a fluid under pressure to the other end of the cylinder whereby the piston is advanced in the cylinder to supply a detergent to the brush from the cylinder.

2. The structure of claim 1, with a second liquid supplying conduit carried by the housing and discharging adjacent the discharge end of the first conduit.

70 In testimony whereof we affix our signatures.

WILLIAM TOMAS PEEK.
LOVELACE P. EUBANKS.
